UNITED STATES PATENT OFFICE

NORMAN W. HOFFMAN, OF BLOOMSBURG, PENNSYLVANIA, ASSIGNOR TO THE MAGEE CARPET CO., OF BLOOMSBURG, PENNSYLVANIA, A CORPORATION OF PENNSYLVANIA

MANDREL FOR CARPET ROLLING MACHINES

Application filed June 10, 1932. Serial No. 616,559.

This invention relates to machines for forming narrow strip or wide web goods, and particularly pile carpets, into tightly wound rolls.

- 5 The object of the invention is to provide a collapsible mandrel for web-winding machines on which the goods is adapted to be wound and which may be readily removed from the completed roll.
- 10 Another object of the invention is to provide the mandrel with novel mechanism for tightly gripping the end of the strip over a minimum area of the goods adjacent the said end thereof and which is readily releasable from the goods to permit the mandrel to be removed from the finished roll.

The construction and operation of the mechanism forming the subject of the present invention will be fully disclosed herein-
20 after, reference being had to the accompanying drawings, of which:

Fig. 1 is a perspective view of the improved mandrel in operating position in a web-winding machine;

25 Fig. 2 is a face view of the mandrel shown in Fig. 1;

Figs. 3 and 4 are respectively right and left end views of the mandrel as viewed in Figs. 1 and 2;

30 Figs. 5 and 6 are transverse sectional elevations taken on the line 5—5, Fig. 2, and respectively showing the combined gripping and roll-collapsing means in inoperative and operative positions;

35 Fig. 7 diagrammatically illustrates the mandrel in cooperative relation to the other elements of the winding machine.

The mandrel 1 comprises a body section 2 in the form of a hollow cylinder, a segmental 40 section of which is eliminated to form an opening 3 extending the full length of the mandrel.

The hollow body cylinder 2 is provided at one end with an integral segmental head 4 from which projects a square trunnion 5 in axial alignment with the cylinder 2.

45 At its opposite end the cylinder 2 is provided with a readily removable full circular head 6 to which the cylinder 2 is secured by 50 tap bolts 7. Extending from the head 6 in

axial alignment with the cylinder 2 and trunnion 5 is a circular trunnion 8.

Pivottally mounted in the heads 4 and 6 respectively are trunnions 9, 9 of an elongated segmental element 10 which are disposed in eccentric relation to the axis of the main body cylinder 2.

55 The element 10 is provided with a segmental eccentric cam surface 11 which when the element 10 is in the inoperative position shown in Fig. 5 provides a slot 12 between its longitudinal corner edge 13 and a longitudinal corner edge 14 of the body 2 at one side of the opening 3 in the mandrel 1, for the reception of one end of a strip of 60 goods α to be wound in a roll on the mandrel 1.

65 When the element 10 is swung about the axes of its trunnions 9, 9 from the position shown in Fig. 5 to that shown in Fig. 6 the end of the strip α is firmly gripped between the eccentric cam surface 11 of the element 10 and the gripping edge 14 of the cylinder body element 2.

70 When the element 10 is in the position 75 shown in Fig. 6 the eccentric cam surface 11 thereof substantially fills and practically closes the opening 3 in the mandrel and forms a spirally tangent continuation of the outer bearing surface 15 of the cylinder body 2 of 80 the mandrel on which the goods is wound, due to the eccentricity of the surface 11 relative to the axes of the trunnions 9 of the element 10 and the eccentricity of the trunnions 9 with respect to the axes of the trunnions 85 5 and 6 of the mandrel 1.

85 The combined cylinder closing and gripping element 10 is adapted to be rocked within the hollow body 2 by a lever 16 secured to or in the hub 17 of the element 10 90 adjacent the full circular head 6 of the mandrel 1, said operating lever 16 being adapted to engage a stop pin 18 projecting inwardly from said head to maintain the element 10 in correct position for its corner 95 edge 13 to form, together with the edge 14 of the cylinder body 2, the slot 12 for the reception of the end of the strip α .

The mandrel 1 is adapted to be supported between and rotated by a pair of axially 100

aligned short shafts 20 and 21 respectively, mounted in bearings 22 and 23 secured to or formed in side frames 24 and 25 of a machine which also supports a rough faced retarding roll 27, a pressure and measuring roll 28, guide rolls 29, 30 and 31 and a lint-removing rotating brush 32.

The short shaft 20 is provided with an axially aligned squared opening for the reception of the squared trunnion 5 of the mandrel 1, and the short shaft 21 is provided with a head 33 having an axially aligned circular opening for the reception of the round trunnion 8 of the mandrel 1.

15 The short shaft 20 is adapted to be rotated from any suitable readily controllable source of power through a train of gears including a spur gear 34 secured to the outer end of the short shaft 20.

20 The short shaft 21 acts as a support for the opposite end of the mandrel 1 and is readily movable in an axial direction for releasing the head 33 from the mandrel trunnion 8, by means of a lever 35 operatively connected to the short shaft 21, whereby the mandrel with the roll of goods thereon may be readily removed from the machine.

By throwing the lever 16, and consequently the combined filling and gripping element 10, from the operative position shown in Fig. 6 to the inoperative position shown in Fig. 5 the end of the strip 8 is released and the effective bearing surface between the mandrel 1 and the innermost lap of the goods is reduced to such an extent that the mandrel is relatively loose in the roll of goods and may be readily withdrawn therefrom, the inner end of the strip 8 which lies within the hollow cylinder 2 of the mandrel moving longitudinally along the slot 12 and through an opener 36 formed between the edge 37 of the segmental head 4 of the mandrel and the adjacent inner surface 38 of the cylindrical body 2, which is aligned with the slot 12 formed between the gripping surface 11 of the element 10 and the edge 14 of the cylindrical body 2.

From the above, it will be quite obvious that with the arrangement of elements 2 and 10 arranged as described there is provided a readily collapsible mandrel and readily operable gripping means for the goods which due to the eccentricity of the gripping and opening filling surface 11 of the element 10 permits a reduction in the effective bearing surface of the mandrel which will permit the mandrel to be readily removed from the completed roll of goods.

I claim:

60 1. A collapsible mandrel comprising a cylindrical body member having a longitudinal segmental opening in the periphery thereof, and a member mounted for circular movement in and relative to said body member and provided with a curved surface normally dis-

posed in said opening in substantially tangent relation to the periphery of the cylindrical body member.

2. A collapsible mandrel comprising a cylindrical body member having a longitudinal segmental opening in the periphery thereof, and a member mounted for circular movement in and relative to said body member and provided with a curved surface normally disposed in said opening in substantially tangent relation to the periphery of the cylindrical body member adjacent one side of the opening and spaced inwardly from said periphery at the opposite side of the opening and gripping the material to be wound on the mandrel between said curved surface and the adjacent edge of the opening in the body member.

3. A collapsible mandrel comprising a cylindrical body member having a longitudinal segmental opening in the periphery thereof, a member mounted for circular movement in and relative to said body member and provided with a curved surface normally disposed in said opening in substantially tangent relation to the periphery of the cylindrical body member adjacent one side of the opening and spaced inwardly from said periphery at the opposite side of the opening and gripping the material to be wound on the mandrel between said curved surface and the adjacent edge of the opening in the body member, and a head at one end of the cylindrical body member having an opening in line with the opening between the said curved surface of the one member and the adjacent gripping edge of the opening in the other member to permit withdrawal of the gripped portion of the material from the mandrel as the mandrel is withdrawn from the material wound thereon.

4. A collapsible mandrel comprising a hollow cylindrical body member having a longitudinal segmental opening therein, a head at each end of said body member, a member pivotally mounted in said heads and provided with an eccentrically curved surface movable to a position in said opening with one edge in tangent relation to the peripheral surface of the body member adjacent one side of the opening providing maximum effective winding surface on the mandrel and movable to a position within said cylindrical body member reducing said winding surface to a minimum.

5. A collapsible mandrel comprising a hollow cylindrical body member having a longitudinal segmental opening therein, a head at each end of said body member, a member pivotally mounted in said heads in eccentric relation to the axis of the body member and provided with a curved surface eccentric to the axes of said members respectively and movable to a position in said opening with one edge in tangent relation to the peripheral surface of the body member adjacent one side

of the opening providing maximum effective winding surface on the mandrel and movable to a position within said cylindrical body member reducing said winding surface to a minimum.

6. A collapsible mandrel comprising a hollow cylindrical body member having a longitudinal segmental opening therein, a head at each end of said body member, a member pivotally mounted in said heads and provided with an eccentrically curved surface movable to a position in said opening with one edge in tangent relation to the peripheral surface of the body member adjacent one side of the opening and in inwardly spaced relation to said peripheral surface adjacent the opposite side of said opening to press the material to be wound on the mandrel into gripping contact with the edge of the body member at the last said side of the opening and providing maximum effective winding surface on the mandrel.

7. A collapsible mandrel comprising a hollow cylindrical body member having a longitudinal segmental opening therein, a head at each end of said body member, a member pivotally mounted in said heads and provided with an eccentrically curved surface movable to a position in said opening with one edge in tangent relation to the peripheral surface of the body member adjacent one side of the opening and in inwardly spaced relation to said peripheral surface adjacent the opposite side of said opening to press the material to be wound on the mandrel into gripping contact with the edge of the body member at the last said side of the opening and providing maximum effective winding surface on the mandrel, and means for swinging said eccentrically surfaced member to a position within the body member wherein the said tangent edge of said curved surface lies adjacent to and spaced from the said gripping edge of the body member, to release the material and to reduce the winding surface of the mandrel to a minimum to permit withdrawal of the mandrel from the roll of material thereon.

8. A collapsible mandrel comprising a hollow cylindrical body member having a longitudinal segmental opening therein, a head at each end of said body member, a member pivotally mounted in said heads and provided with an eccentrically curved surface movable to a position in said opening with one edge in tangent relation to the peripheral surface of the body member adjacent one side of the opening and in inwardly spaced relation to said peripheral surface adjacent the opposite side of said opening to press the material to be wound on the mandrel into gripping contact with the edge of the body member at the last said side of the opening and providing maximum effective winding surface on the mandrel, and means for swinging said eccentrically surfaced member to a position within the body member wherein the said tangent edge of said curved surface lies adjacent to and spaced from the said gripping edge of the body member, to release the material and to reduce the winding surface of the mandrel to a minimum to permit withdrawal of the mandrel from the roll of material thereon.

centrally surfaced member to a position within the body member wherein the said tangent edge of said curved surface lies adjacent to and spaced from the said gripping edge of the body member, to release the material and to reduce the winding surface of the mandrel to a minimum to permit withdrawal of the mandrel from the roll of material thereon, one of said heads having an opening in line with the opening provided between the said spaced edges of the body and gripping members to permit the previously gripped portion of the material to move out of the mandrel during withdrawal of the mandrel from the roll of material.

9. A collapsible mandrel comprising a hollow cylindrical body member having a longitudinal segmental opening therein, a head at each end of said body member, a member pivotally mounted in said heads and provided with an eccentrically curved surface movable to a position in said opening with one edge in tangent relation to the peripheral surface of the body member adjacent one side of the opening and in inwardly spaced relation to said peripheral surface adjacent the opposite side of said opening to press the material to be wound on the mandrel into gripping contact with the edge of the body member at the last said side of the opening and providing maximum effective winding surface on the mandrel, and a lever connected to said eccentrically surfaced member and projecting beyond the said peripheral surface of said body member adjacent one of said heads for swinging said eccentrically surfaced member to a position within the body member wherein the said tangent edge of said curved surface lies adjacent to and spaced from the said gripping edge of the body member, to release the material and to reduce the winding surface of the mandrel to a minimum to permit withdrawal of the mandrel from the roll of material thereon, the other of said heads having an opening in line with the opening provided between the said spaced edges of the body and gripping members to permit the previously gripped portion of the material to move out of the mandrel during withdrawal of the mandrel from the roll of material.

10. A collapsible mandrel comprising a hollow cylindrical body member having a longitudinal segmental opening therein, a head at each end of said body member, a member pivotally mounted in said heads and provided with an eccentrically curved surface movable to a position in said opening with one edge in tangent relation to the peripheral surface of the body member adjacent one side of the opening and in inwardly spaced relation to said peripheral surface adjacent the opposite side of said opening to press the material to be wound on the mandrel into gripping contact with the edge of the body member at the last said side of the opening and providing maximum effective winding surface on the mandrel.

and providing maximum effective winding surface on the mandrel, a lever connected to said eccentrically surfaced member and projecting beyond the said peripheral surface of said body member adjacent one of said heads for swinging said eccentrically surfaced member to a position within the body member wherein the said tangent edge of said curved surface lies adjacent to and spaced from the said gripping edge of the body member, to release the material and to reduce the winding surface of the mandrel to a minimum to permit withdrawal of the mandrel from the roll of material thereon, the other of said heads having an opening in line with the opening provided between the said spaced edges of the body and gripping members to permit the previously gripped portion of the material to move out of the mandrel during withdrawal of the mandrel from the roll of material, and means for limiting the said swinging movement of said eccentrically surfaced member relative to the body member to maintain the said open relation between the said edges of said members for receiving the material to be gripped and wound by and on the mandrel.
